WOOD CHECKERING MACHINE

John Crowe, St. Joseph, Mo., assignor to Olin Mathieson Chemical Corporation, a corporation of Virginia

Application March 5, 1957, Serial No. 644,041

9 Claims. (Cl. 144—136)

The present invention relates to checkering machines and in particular to automatic checkering machines adapted to checker gun stocks. The invention also relates to a process practiced by the operation of the machine.

It is a particular object of the invention to provide an automatic machine adapted to receive a wooden or plastic work piece such as a forearm of a rifle or shotgun and to perform a cutting operation thereon in accordance with a predetermined pattern.

A particular object of the present invention is the provision of a machine adapted to receive a work piece and to carve at least two independent and separate areas thereof in automatic fashion and in sequence without any manipulation by an operator.

A further object of the invention is to provide a machine of the above general character which, when set in motion, will accomplish in sequential fashion a variety of operations and which, upon the completion of the operations, will automatically shut down.

It is a still further object of the present invention to provide a machine whose operation involves the practice of a novel process.

In general, a machine embodying certain principles of the present invention may include an arbor for supporting a work piece such as a walnut forearm of a gun stock and a circular milling cutter mounted adjacent the work piece and adapted to mill grooves therein. Means are provided for rotating and reciprocating the work piece with respect to the milling cutter so that, in effect, the cutter may be said to be generating a thread having a predetermined angle of lead. Since the work is rotated or oscillated through a predetermined arc while it is reciprocated axially, the cutter head is held stationary while accomplishing a single cut.

Automatic means are also provided for reversing the rotation of the work piece and for changing the angular position of the cutter head. This action is effective to cut grooves or threads, initially, with a left hand lead and thereafter with a right hand lead or vice versa. In this fashion, a knurled effect, known as checkering, is achieved on the surface of the work piece. In effect, a plurality of small raised portions having a diamond or pyramid shape are created.

Means are also provided for controlling the cutter whereby the cutter may be moved away from the work during certain intervals and thereafter moved towards the work so that the checkering falls within a predetermined area to define a desired pattern.

As stated previously, the work piece is oscillated through a predetermined arc while it is reciprocated. Thus, if for the interval of each cut, one were to assume that the milling cutter mounting remains stationary, it is readily apparent that a single groove or thread will be milled in the work piece as the work is oscillated and reciprocated simultaneously. It is to be understood that to accomplish a given cut in the work piece, it is necessary for the work piece to rotate first in a

2

clockwise direction through a predetermined arc and thereafter counterclockwise through the same arc. Correspondingly, during the occurrence of the clockwise rotation, the work piece is also reciprocated forwardly and thereafter returned through a given distance. Milling of a thread or groove occurs only during the combined clockwise rotation and forward reciprocation of the work piece, the cutter being raised away from the work during return strokes.

10 After each single cut has been accomplished, means are provided for indexing the milling cutter head a predetermined distance along the work piece to provide new surface for milling a new thread.

After all cuts have been accomplished (having a left-hand or right-hand lead as the case may be) the milling cutter is shifted automatically to a new angular position with respect to the work and the oscillatory cycle of the work piece is reversed correspondingly so that thereafter threads or grooves of the opposite hand are milled.

15 20 Means are provided for indexing the cutter in both axial directions so that the cutter first is indexed from left to right as viewed in Fig. 1 to make the first series of cuts of one hand and thereafter indexed from right to left to make the cuts of the opposite hand.

25 Usually a forearm is checkered in accordance with a desired pattern on opposite sides. Accordingly, means are provided by the present invention for rotating the work piece automatically when a first side is completed to present the opposite side of the work piece to the milling cutter. Thereafter the general operation just described is repeated automatically.

30 Ultimately when both sides of the work piece are completed, a counter means is effective to shut down the machine whereupon the operator may remove the finished work piece and recharge the machine.

The cutting head is also provided with a novel means for assuring uniformity of depth of grooves throughout the full checkering pattern in spite of variations or unevenness in the surface of the rotating work piece.

35 40 Other features and advantages of the present invention will become more apparent from an examination of the succeeding specification and drawings, in which:

Fig. 1 is a perspective view of the complete machine;
Fig. 2 is a perspective view of the cutting head assembly;

45 Fig. 3 shows a trigger and latch mechanism utilized to cast the cutting head from a right hand thread cutting position to a left hand thread cutting position and vice versa;

50 Fig. 4 shows a flip-over or gear change device utilized to change the direction of rotation of the work piece;
Fig. 5 is a perspective view of the cutting head indexing mechanism with certain portions thereof broken away;

55 Fig. 6 is a view of the portion of the showing of Fig. 5 illustrating the elements utilized to engage and disengage the indexing pawls;

Fig. 7 is also a view of a portion of Fig. 5 showing to advantage the cooperation between the indexing pawls and the driving link therefor;

60 Fig. 8 is a perspective view of the cutting head yoke including the indexing racks and cam contactor;

Fig. 9 is an exploded view of the clutch mechanism;
Fig. 10 shows the clutch actuating yoke;

65 Fig. 11 is a schematic showing of the arrangement of the contact cams, one contact cam being utilized to cut right hand grooves, the work piece and the other contact cam being utilized to cut the left hand grooves;

Fig. 12 is a schematic showing of the angle through which the cutting head is rotated when shifting from a right hand groove or thread cutting position to the opposite hand or vice versa;

Fig. 13 is a showing of the counter device utilized to shut down the machine upon the completion of a work piece; this device is mounted upon the back side of the machine as viewed in Fig. 1;

Fig. 14 is a similar view showing the counter device in the shut down condition.

Fig. 15 is a wiring diagram utilized to control the checkering machine;

Fig. 16 is a schematic showing of the relative positions of the work piece and the cutting head while checkering is being accomplished in work area No. 1;

Fig. 17 is a similar showing of the same elements while checkering is being accomplished in work area No. 2; and

Fig. 18 is a vertical section of a portion of the cutting head of Fig. 2 as viewed in the plane of the line 18-18.

Referring now to the drawings and in particular to Figs. 1 through 7, there is shown a main support member comprising a channel 10. Three main vertical supports 11, 12 and 13 are spaced along the channel 10. Supports 11 and 12 define, in general, the area within which the checkering machine is driven and controlled, while the area of the machine between the supports 12 and 13 is occupied by the work piece and the cutting head.

In the embodiment of the invention illustrated in Fig. 1, the work piece is a wooden forearm of a conventional firearm usually of walnut and designated here by the reference numeral W.

Referring now in detail to the power and control area of the machine defined by the vertical supports 11 and 12 and for convenience referred to hereinafter by the reference numeral 14, there is shown a main power sheave 16 connected to a gear box 17. The gear box supplies power to a crank 18 which, in turn, reciprocates a lever 19. The lever 19 reciprocates a primary rack 21 which is in engagement with a gear sector 22.

The gear sector 22 is keyed to and carried by a stub shaft 23 supported on a vertical web member 24 suitably mounted upon the channel 10. Upon the opposite side of the web 24 a stub shaft 23 carries another gear sector 26 (shown in dotted lines) in engagement with a sliding rack 27. It is to be noted that the gear sector 26 is generally of the same diameter as the gear sector 22; however, the stub shaft 23 also carries an additional gear sector disposed in the same vertical plane as the sector 26 but of larger diameter. This latter sector, indicated by the reference numeral 28, is utilized to reciprocate the work piece W from right to left as viewed in Fig. 1 in a manner which will become more apparent hereinafter.

Referring now in detail to Figs. 1 and 4, it is apparent that sliding rack 27 has a projection which engages still another gear sector 29. Sector 29 in turn engages and reciprocates a relatively short rack 31.

The short vertical rack 31 carries a flip-over or gear change device which is operable to cause the rack to drive one or the other of a pair of work rotating racks indicated by the reference numerals 32 and 33 respectively.

Short rack 31 carries a generally triangular-shaped rock lever 34 having oppositely disposed arms 36 and 37 respectively. The rock lever 34 is pivotally mounted to the rack 31 by means of the pin 35 and is also provided with a suitable spring pressed detent 38 effective to encourage the rock lever to rock from the position shown in Fig. 4 wherein the rotating rack 32 is being driven to a second position corresponding to a condition in which the rack 33 is being driven.

It is to be noted that a cross slide 39 is also mounted in the short rack and carries a pin 41 which engages a cooperating recess 42 in the rock lever. In this manner, when the rock lever 34 is rocked to and fro in the directions indicated by the arcuate arrow in Fig. 4, the rock lever by virtue of the cooperation of the pin 41 and the

recess 42 acts to cast the cross slide 39 from the position shown in Fig. 4 wherein the tip 43 thereof is in engagement with a notch 44 formed in the rack 32 to a position wherein the tip 46 thereof will engage a corresponding notch 47 formed in the rack 33.

Thus, by virtue of the rock lever and cross slide carried by the reciprocating short rack 31, it is possible to cause the rack 31 to drive the rack 32 or the rack 33, in turn causing gear 58 to revolve clockwise or counterclockwise during the upward stroke of short rack 31.

The manner of accomplishing flip-over of the rock lever is as follows:

As stated before, the rack 31, which carries the rock lever 34 and the cross slide 39, is constantly reciprocated vertically by the gear sector 29. The cross slide may be in driving engagement with either the rack 32 or the rack 33. It is also to be noted that there is sufficient clearance between the ends of a pair of guide bars 48 (rigidly mounted to the web 24 in a manner more apparent in Fig. 1) to permit the rock lever and the cross slide to pass between the ends of the bars 48 and the face of vertical rack slides 49. A block 51 rigidly mounted to the bars 48 carries a horizontal shift lever 52 pivotally mounted to the block by a pin 53.

The shift lever is pivotally connected to a timing rod 54 so that reciprocation of the timing rod along the path indicated by the arrows of Fig. 4 will operate to rotate the shift lever. When the timing lever is withdrawn or moved to the left as shown in Fig. 4, a projection 56 of the shift lever is cast into the path of the reciprocating rock lever 34 such that the arm 36 of the lever is engaged by the projection 56 and the rock lever is cast to the left to the position shown in Fig. 4.

Correspondingly, the cross slide 39 is cast to the left and the tip 43 thereof finds its way into the notch 44 of the rack 32 thus making a driving connection between rack 31 and rack 32. After a predetermined interval and in sequential fashion, the timing rod 54 is automatically moved to the right as viewed in Fig. 4 thus placing a projection 57 of the shift lever 52 into blocking position with respect to the blocking lug 37 of the rock lever. When the projection 57 and the lug 37 collide, the rock lever is cast to the right as viewed in Fig. 4 causing the tip 46 of the cross slide 39 to engage the notch 47 formed in the rack 33. In this manner, power has been withdrawn from the rack 32 and applied to the rack 33.

Pinion 58, driven for a predetermined interval by the rack 32 and thereafter by the rack 33, constantly oscillates through a predetermined arc and is carried by a main shaft 59 suitably journaled in the support 11. As will be apparent from the showing of Fig. 1, shaft 59 runs the full length of the machine and rotates the work piece W through a corresponding arc.

The main shaft 59 is suitably journaled in the support 12 and in the support 13 and also carries a pinion 61 adjacent the support 12 for driving a pair of cam pinions 62 and 63 in a manner which will become more apparent hereinafter.

The shaft 59 carries a sleeve 64 slidably mounted thereon and formed on the underside thereof with a rack adapted to engage the teeth of the large gear sector 28. Since the gear sector 28 constantly oscillates with the stub shaft 23, the sleeve 64 is caused to reciprocate to and fro along the shaft 59 while the shaft 59 rotates in oscillatory fashion. The sleeve 64 is formed with an undercut groove or keyway 66 adapted to receive the heads 67 of a pair (only one shown) of elongated keys 68 slidably received in the shaft 59 as is apparent at 69.

It is to be noted that the keys 68 are rigidly connected to the work W and function to cause the work to reciprocate in the direction shown by the arrows of Fig. 1 while the work is oscillated through a predetermined arc by pinion 58.

There is no jamming action with respect to the re-

ciprocating motion generated in the sleeve 64 as against the oscillatory or rotary motion generated in the shaft 59 because the heads 67 of the keys 68 are free to rotate in the annular keyway 66 formed in the sleeve.

The mechanisms just described are operable in the manner shown to generate the basic motions necessary to operate the checkering machine of the present invention. In effect, the work piece is rotated in oscillatory fashion and reciprocates simultaneously in a manner such that if the work is moved relative to a stationary cutting element, a groove having a predetermined lead or a spiral is milled in the work piece.

For example, with the cutting head in the position shown in Fig. 1, and with the flip-over mechanism of Fig. 4 in the condition shown therein, the work piece W is rotated towards and away from the cutting head while it is moved axially along the axis of rotation so that a groove corresponding to the groove 61 is milled in the work piece.

Cutting head

At this point it may be well to point out that the cutting head carries a circular milling cutter and means are provided for controlling physical contact of the cutter with respect to the work piece W so that the depth of cut may thereby be controlled and, too, so that the cutter is maintained clear of the work during the return portions of both the oscillatory and reciprocatory strokes.

The means for moving the cutting element into and out of engagement with the work will now be described. In this connection, a reference to Figs. 2, 8 and 18 will be helpful.

The cutting head indicated generally by the reference numeral 71 is pivotally mounted upon a yoke 72 in turn pivotally mounted upon a plate 73. The cutting head 71 is so balanced in the yoke 72 that gravity tends to pull the left portion thereof, as viewed in Fig. 2, downwardly towards the work piece W. The plate 73 is secured to a pair of feed racks 74 and 76 as is most apparent in Fig. 8. The racks, slidably received in slots formed in the underside of rigid bar 88, are utilized to move the cutting head along the work piece in a manner which will become more apparent hereinafter.

The forward portion of the cutting head is secured to an armature 79 integral with an electromagnet 81. The magnet, when energized, is operative to pivot the cutting head downwardly to aid gravity and to oppose a leaf spring element tending to lift the cutting head away from the work in a manner which will become more apparent hereinafter.

For assuring the accomplishment of a uniform depth of cut a pair of followers 83 and 84 are slidably mounted within a bracket 86 which in turn makes a lost motion connection with the cutting head wherein the bracket is pivotally supported by the pin 87. The bracket 86 is urged to move downwardly relative to the cutting head by a leaf spring 85 suitably secured to the cutting head and bearing upon a pin 90 supported in the bracket 86. A rigid bar 80 secured to the cutting head normally engages a projection 88a formed on the bracket 86 and is effective to limit the relative motion between the bracket and the head and thus between the cutting element 82 and the followers 83 and 84. The position of the elements 80 and 88a in Fig. 18 represents their normal position and it is to be noted that normally the cutting element 82 is withdrawn with respect to the followers 83 and 84. Although the followers normally ride upon the work piece, energization of the magnet 81 will cause the armature 79 to pull the cutting head 71 downwardly causing the cutting element 82 to pivot about yoke 72. The force exerted by the solenoid is sufficient to overcome the tendency of the spring 85 to urge the cutting element upwardly with respect to the followers 83 and 84 and as a result, the cutting element is moved to the dotted line position shown in Fig. 18. In this condition, the

cutting element is free to mill a groove in the work piece and the depth of the groove is regulated by the prior setting of the set screw 88b with respect to a stop 88c.

The pair of followers 83 and 84 are slidably disposed in the bracket 86, as stated previously, and are carried by a cross pin 86a in turn supported by a rotatable pin 90.

The axis of rotation of the pin 90 is co-planar with the vertical plane which includes the maximum diameter of the cutter. The pivotal mounting of the followers 83 and 84 in conjunction with their ability to slide upwardly and downwardly assures a uniform depth of cut during the occurrence of variations in surface contour or radius of the work piece.

It is to be understood that the followers actually ride on the work at all times; however, when the solenoid 81 is not energized the cutting element remains withdrawn above the lowermost portions of the followers therefore no cutting occurs even though the cutting element is rotating. Energization of the solenoid merely hauls the cutting element downward a predetermined distance beyond the lowermost portions of the followers and cutting occurs.

Indexing

As stated previously, means are provided for indexing the cutting head in incremental fashion along the work piece W after each cut has been completed.

Referring again to Figs. 1, 2, 5 and 8, it is apparent that the cutting head slides along a rigid bar 88 wherein feed racks 74 and 76 are provided with extensions which carry the cutter yoke 72. Feed rack 74 is utilized to index the cutting head from left to right as viewed in Fig. 1 while feed rack 76 is utilized to index the cutting head from right to left. A timing bar is provided for placing one feed rack or the other in operation and correspondingly rendering the other inoperative in sequential fashion. The power for the indexing mechanism is provided by sliding rack 27 (Fig. 5) wherein one end thereof is provided with a cross pin 89 straddled by a pair of feed levers 91 and 92.

A reference to Figs. 5, 6 and 7 will make this structure more apparent. Note that the elements are shown as viewed from the opposite side of the showing of Fig. 1.

The feed levers are pivotally mounted individually to the vertical support 12 as at 93 and each carries a pivotally mounted pawl or dog 94. Each dog is adapted to engage a corresponding rack and are effective to advance the cutting head a predetermined distance in one direction or the other, depending upon which dog is engaged, as the slide rack 27 is reciprocated.

The dogs are brought into and out of engagement with their corresponding racks by a pair of rock levers 96 pivotally mounted to the vertical support 12 and actuated by a timing bar 97. Each rock lever is provided with a projection 98 which cooperates with a pin 99 formed on each dog.

As is apparent in Fig. 6, rotation of the rock lever in the direction shown by the arrow will cause the projection 98 to contact the pin 99 thereby camming the dog upwardly out of engagement with its corresponding rack. Both rock levers are generally of the same construction, however, the projections 98 are formed on opposite sides thereof so that when the timing bar 97 pivots the rock levers, one lever operates to drop a dog into engagement with its corresponding rack while the other lever operates to disengage the opposite dog from its rack.

Timing bar

As is apparent, a great number of mechanical operations occur automatically in the course of checkering a work piece utilizing the machine of the present invention. Basically, all the mechanical operations are tied to and initiate in response to the action of the timing bar 97 referred to above. The timing bar 97 is an elongated element slidably mounted beneath the rigid bar 88 and

has a projection thereof in the form of a rod 54 extending towards vertical support 11. It will be recalled that the timing rod 54 was discussed in connection with the operation of the flip-over mechanism for changing rotation of the work piece. The connection between the timing rod 54 and the timing bar 97 is accomplished through the instrumentality of the rock levers 96 as will be apparent in Fig. 5.

The timing bar contains an elongated slot 101 engaged by a depending lug 100 mounted upon the cutting head. The timing bar and its accompanying rod are shifted in the direction of the arrows shown in Fig. 2 by the engagement of the lug 100 with the corresponding end of the slot 101 as the cutting head is indexed to its extreme right-hand or left-hand positions as viewed in Fig. 1.

The timing bar 97 and its extension 54 control (1) the gear change or flip-over mechanism (2) the actuation of selector switch 143 and (3) the engagement and disengagement of the indexing pawls or dogs 94.

Reversal of angular position of cutting head

As is apparent in Fig. 12, the cutting head is first disposed with respect to the work piece W in a first angular position. While in this angular position, the cutting head is indexed after accomplishing each cut along the full length of the desired pattern accomplishing a plurality of parallel cuts. Upon completion of these cuts, the head is automatically shifted from a position indicated in Fig. 12 by the reference numeral 102 to a position indicated by the reference numeral 103 and a new series of parallel cuts are accomplished making an included angle of approximately 55 degrees with respect to the cuts formed by the previous position of the cutter.

Incidentally, it is to be noted that at the time of occurrence of the shift of the cutter from position 102 to 103, the cutting head has actuated the timing bar to cause the indexing mechanism to shift from one indexing rack to the other.

A reference to Figs. 2 and 3 will reveal the mechanism that is utilized in accomplishing the angular shifting of the cutting head. Fig. 3 is a perspective view of the underside of the head support and for purposes of explanation, the plate member 104 may be considered integral with the yoke element 72. These members are both pivotal about the pin 106 and are connected by the post 107. The plate 104 is formed with a finger 108 disposed between a pair of cocking springs 109. The plate also carries a pair of oppositely disposed notches 111 engageable by corresponding pivotally mounted triggers 112. As the cutting head assembly approaches an extreme position marking the end of a predetermined group of parallel cuts, a spring housing 113 slidably mounted in the bearings 114 encounters a stop or an abutment such as the abutment 116. Continued indexing of the cutting head causes the spring housing to slide through the bearings 114 thus compressing the adjacent cocking spring 109 against the finger 108. The plate 104 is held against rotation about the pin 106 wherein the trigger 112 and the corresponding lug 111 are latched in the manner shown in Fig. 3.

Further indexing of the cutting head towards the end of its run moves the latched trigger 112 towards another abutment such as the abutment 117. Upon contact the dog is unlatched and the compressed cocking spring 109 operates to rotate (in the direction of the arrow of Fig. 3) the plate 104 including the yoke 72 and the cutting head through an angle of approximately 55 degrees or to the position shown by the reference numeral 104 in Fig. 12. At this time, the opposite trigger and its corresponding notch 111 latch the cutting head firmly in position.

It is to be understood that the abutments 116 and 117 respectively are mounted upon the vertical support 13 and that corresponding abutments are provided upon the

vertical support 12. The latter are effective as the cutting head is indexed to the opposite end of its path of travel.

Turning the work piece

As stated previously, it is frequently desirable to checker a given pattern on one area of a work piece and thereafter checker the same pattern on the opposite side; consequently, the checkering machine of the present invention includes means for automatically turning the work piece W from a first work position to a second work position for the purpose of forming an identical pattern in at least two different areas.

Referring now to Figs. 1, 9 and 10, it will be apparent that the main shaft 59 is provided with a clutch indicated generally by the reference numeral 118. The clutch comprises a driving element 119, a driven member 121 and a locking member 122. An operating yoke 123 is formed with an arcuate portion 124 adapted to engage an undercut portion 126 formed on the locking member. The yoke is pivotally mounted to the block 51 and carries a pair of operating arms 127 having cam surfaces 128 formed on the undersides thereof and engageable with a follower 129 formed on one of the feed racks.

As the feed racks are indexed from left to right as viewed in Fig. 10, the follower 129 constantly approaches the cam surface 128. After the cutting head is indexed to the position for cutting the last groove in a given series of cuts, the next indexing operation causes the follower 129 to cam the yoke in the direction shown by the arrow of Fig. 10 with the result that the locking member 122 is moved out of driving engagement with respect to the driving member 119 wherein the lugs 131 are moved beyond driving surface 132.

During the moment of disengagement, a suitable coil spring (not shown) is free to cause the driven member 121 and locking member 122 to rotate or to be phased approximately 180 degrees with respect to the driving member whereby the lugs 131 encounter stops 133. The stops limit the phasing to 180 degrees.

During this occurrence the timing bar 97 has been actuated by the lug 100 (Fig. 2) depending from the cutting head to cause the indexing to be reversed so that upon the next stroke of the slide rack 27 the follower 129 moves away from the cam surface 128 permitting the yoke to return the locking element 122 into a driving connection with the driving element 119.

A second predetermined work area, namely, the opposite side of the work piece W having been presented to the cutting head, the machine automatically begins to perform cutting operations upon this new area of the work.

A more detailed explanation of the sequence cutting operations will be presented hereinafter.

Electrical control cams

As stated earlier, electrical means are provided for controlling the checkering pattern. This is accomplished by sending an electrical signal to the cutting head solenoid which is effective to cause the solenoid to pull the cutting element into the work at a predetermined time interval permitting the cutting element to mill a groove of predetermined length as the work is rotated and oscillated and thereafter the signal operates to de-energize the cutting head solenoid effective to terminate cutting, thereby limiting the length of groove and permitting the work to accomplish its return stroke without engaging the cutter.

Obviously, the parallel grooves formed while the cutting head is in the position represented by the reference numeral 103 in Fig. 12 and those of the opposite hand formed when the cutting head is in the position designated by the reference numeral 102 in Fig. 12 must be controlled so that the ultimate configuration or outline of checkering falls within a predetermined area.

For example, a pattern on work piece W shown in Figs. 1 and 12 is representative of such an outline.

In order to control the cutting element and the cutting head to accomplish the desired pattern, four contact cams are provided.

For reasons that will become more apparent hereinafter the electrical contact cams are provided in pairs, one pair effective to control the grooves formed while the cutting head is in the position represented by the reference numeral 102 and the other pair effective to control the grooves milled when the cutting head is in the position represented by the reference numeral 103 of Fig. 12.

Referring now to Figs. 1, 8, 11 and 12, the pairs of contact cams are designated by the reference numerals 134 and 135 mounted on shafts 136 and 137 respectively in turn supported for rotation in the vertical supports 11 and 12.

It is noted that the shafts carry pinions 62 and 63 in driving engagement with main shaft pinion 61.

Since the function and structure of each pair of cams is substantially identical, the structure and operation of only one pair thereof will be described in detail, it being specifically understood that one pair of cams is utilized whenever the cutting head is in the angular position represented by the reference numeral 102 while the other pair of cams is utilized when the cutting head is in the 103 position.

It is noted that each pair of cams take the form of a split cylinder and in the case of contact cams 135 comprising an arcuate electrical contact of brass or copper 138 and another, referenced 139. Current is passed through these contact cams to a contactor 141, in the case of pair 135, and 142, in the case of pair 136 (Fig. 8), in a manner which will become more apparent hereinafter. The cams are in circuit with the solenoid 81 which controls cutting head. The configuration or outline of each cam is formed in accordance with the pattern desired to be cut upon the work piece W. For example, as the work piece is rotated, the contact cams will be rotated whereby the arcuate cam 138 or 139, depending upon the phasing of the work piece W, will sweep past the contactor 141. Whenever the cam surface engages the contactor, current will flow into cutting head solenoids to pull the cutting element into the work. When the contact cam sweeps past the contactor 141, the circuit is broken and the cutting head is immediately released from the work.

It is to be noted that the contactors 141 and 142 are mounted upon the feed rack; consequently, they are indexed along the contact cams simultaneously with the indexing of the cutting head.

Pairs of contact cams (such as the segments 138 and 139) of generally identical configuration are provided on each shaft 136 or 137 so that when the work piece is rotated from the first work area to the second work area as described under that portion of the specification entitled "Turning the Work Piece" above, a contact cam will be available for controlling the cutting head in each position of the work piece. As stated before, the pair of contact cams individual to a given shaft control the cutting head while in a given angular position such as represented by the reference numeral 102 while the other pair of electrical contact cams control the cutting head while in the opposite angular position designated by the reference numeral 103.

Current is provided to the contact cams by means of conventional brush and commutator arrangements mounted on the shafts 136 and 137. A cut out switch is provided for breaking the electrical circuit to the brushes in a manner which will be more apparent hereinafter.

By the same token, the current flow through a particular pair of contact cams 133 or 134 is controlled by a selector switch 143 (see Fig. 1) actuated by the cutting head carriage.

Timing

In a typical cycle of operation, the cutting head and the work piece assume the following positions in sequential fashion and the checkering machine correspondingly forms a variety of operations automatically. A reference to Figs. 16 and 17 will show schematically the sequence of these positions. In Fig. 16 the work piece W is shown positioned with the first work area presented to the cutting head. Assume that the cutting head is disposed in position A. Operation of the checkering machine will cause the work piece W to rotate and reciprocate so that a groove is milled in the work piece in the direction shown by the arrow. Obviously, the length of the grooves is controlled by the action of the particular electrical control cams corresponding to position A and to work area No. 1, i.e., cam segment 138 of pairs 135. The cutting head will be indexed along the work piece in the direction shown by the horizontal arrow of Figs. 16 until ultimately the final groove is milled. Upon completion of the last groove the angular position of the cutting head will be reversed simultaneously with the reversal of the direction of rotation of the work piece so that thereafter the cutting head will be in angular position B and the cutting element will begin to mill grooves along the new angular position; the grooves being milled in the direction shown by the arrow.

Obviously, when the cutting head is in position B, the control cam corresponding to the angular position and to the particular work area, is in circuit with the cutting head solenoid, i.e., the timing bar 97 actuates selector switch 143 to place the proper cam segment of the pair of segments 134 in circuit with the magnet 81.

While in position B the cutting head will be indexed in incremental fashion along the work piece until ultimately the desired number of parallel grooves are complete in accordance with the signals controlled by the corresponding electrical contact cam. At this point the clutch is disengaged by the action of the lug 129 upon the cam surface 128 (see Fig. 10) whereupon the clock spring (not shown) causes phasing or rotation of the work piece through 180 degrees to present work area No. 2, represented by the showing of Fig. 17, to the cutting head. While the work piece is being rotated to work area No. 2, the cutting head is flipped from angular position B to angular position A by the operation of the trigger and latch mechanism of Fig. 3. Furthermore, the direction of rotation of the work piece is also reversed by the operation of the gear shift device of Fig. 4. Thereafter the work piece W is in the position shown in Fig. 17 while the cutting head is in angular position A' and the checkering operation proceeds as described in connection with Fig. 16. Thereafter and upon completion of the desired number of threads or grooves from the A' position the head shifts automatically to angular position B'; work rotation having been reversed and the series of grooves corresponding to the B' position of the cutting head are milled.

Upon completion of work area No. 2, a counter mechanism to be described hereinafter is effective to shut down the checkering machine whereupon the work piece may be removed and the machine reloaded.

Counter mechanism

Referring now to Figs. 13 and 14, there is shown a counter mechanism comprising a pivotally mounted dog 146 having an operating arm 147. The dog is pivotally mounted to a bracket 148 in turn secured to the channel 19. A coil spring 149 urges the dog into engagement with rotatable lug 151 having a plurality of projections 152, 153 and 154. Coil spring 149 constantly urges the dog 146 in the direction tending to engage lugs 152 and 153. Cooperating with the rotatable lug 151 is stop lever 156 having a hook portion 157 adapted to engage projection 154.

When the lug 151 is in the position shown in Fig. 14 the stop lever rotates in the direction shown by the arrow in response to the urging of a spring 150 wherein the hook 157 and the projection 154 are engaged. When this rotation occurs, a pin 158 mounted in the upper regions of the stop lever assumes a blocking relationship with respect to a crank arm 159 rigidly secured to stub shaft 23 thus blocking further operation of the machine.

Simultaneously, the opposite end of the stop lever 156 carrying a pin 161 in turn engages a U-shaped switch operating element 162. Consequently, when the stop lever 156 assumes its blocking position the element 162 is moved to the right as viewed in Fig. 14 with the result that a switch 163 operates to open the electrical power circuit to the checkering machine thus shutting it down.

The counter mechanism is operated by the contact of a lug 164 projecting from the underside of the indexing rack 76.

When the cutting head is in position B, the rack 76 is indexed constantly to the right as viewed in Figs. 13 and 14 until ultimately the lug 164 contacts the operating arm 147. When this occurs, the arm 147 is rotated in the direction shown by the arrow and the dog slides to the left and over the lip of lug 152. When the cutting head returns to the left, spring 149 causes the dog 146 to rotate the lug 151.

The counter action occurs for the first time upon the completion of work area No. 1 and corresponding counteraction occurs upon the completion of work area No. 2 wherein the dog 146 engages projection 153 to rotate the lug 151 into a position to receive hook 157 into engagement with projection 154 whereupon switch 163 is opened and operation of the machine is blocked as shown in Fig. 14.

Electrical circuit

Referring now to Fig. 15, there is shown schematically the electrical circuits for controlling the operation of the checkering machine of the present invention.

Current is supplied from a suitable source of power through the lead 166 to the selector switch 143. From the selector switch, depending upon the position thereof, current flows through electrical cam 135 and follower 141 to the junction 167. Of course, if the selector switch is in the opposite position current will flow alternatively through electrical contact cam 134 and follower 142 to the junction 167. These two current flow paths correspond to (1) the A and A' angular position of the cutting head in one case and (2) the B and B' angular position thereof in the other case.

In other words, when the cutting head is making grooves from the A or A' positions depending upon which work area is presented to the cutting element, current is flowing through the electrical contact 135 and follower 141 while when the cutting element is making grooves from the B and B' position current flows to the electrical contact cam 134 and corresponding follower 142.

It is to be understood that when each follower and its corresponding cam are in contact, current flows and that when the contour of the cam is such that there is no physical contact between the two elements, current does not flow in the respective circuits.

From junction 167 current flows through a return stroke switch 168. This switch is located on the main drive sheave 16 and takes the form of a circular commutator segment having a conducting segment of approximately 180° and a non-conducting segment through the remaining 180°. The angular position of this commutator is so phased with respect to the reciprocating and oscillatory rotation of the work piece W that during the return reciprocating and oscillatory strokes the electrical circuit is broken so that there is the assurance that the cutting head magnet will be de-energized and the cutting element correspondingly raised out of contact with the work piece.

A reference to Fig. 16 will provide clarification of the

function of this switch. Assume that the cutting head is in the position A and that the corresponding electrical contact cam and follower having come into physical contact. The cutting head will be pulled into the work and a groove will be milled in the direction of the arrow as work piece W is reciprocated from left to right and rotated towards the cutting element. When the reciprocating stroke has been completed to the left and the rotational stroke has been completed in a direction toward the cutting element, the work piece traverses return strokes to the starting point. It is during this latter interval, corresponding to the return strokes and actual indexing of the cutter that current to the cutting head solenoid 81 is diverted by the return stroke switch 168, thus assuring that the cutting element remains raised out of contact with the work piece.

From the return stroke switch, current flows through the shut down switch 163 normally in a closed position until the counter mechanism operates to break the circuit in a manner previously described. Thereafter current flows through the winding of the cutting head solenoid 81 and thence back to the other side of the line.

It is to be understood that the cutting head motor is energized by a separate circuit and the cutting head motor is maintained in operation constantly.

Loading and unloading the work piece

The work piece W is inserted in the checkering machine by dropping the upper portion 171 of the vertical support 13 about hinge pin 172 in the direction shown by the arrow of Fig. 1. Thereafter the work piece is removed from the shaft 59 by sliding it axially along the shaft to the right. A new and uncheckered piece may thereafter be inserted by performing the above steps in reverse. It is noted that the shaft 59 in the area where the work piece is reversed is formed with an arbor having the general configuration of the interior of the work piece, thus assuring that the work piece is adequately keyed against relative rotation with respect to the shafts.

Operation

Assume that the checkering machine has been loaded with a work piece W and that the cutting head is disposed in position A ready to begin checkering work area No. 1 as shown in Fig. 16. Prior to starting the machine it is necessary to disengage the clutch and wind the clutch spring manually so that upon completion of work area No. 1, the shaft 59 will be automatically phased through 180° with respect to the driving shaft.

It is also necessary to set the counter mechanism in the position shown in Fig. 13.

Thereafter the machine may be set in operation by suitably driving the sheave 16 whereupon the work piece W will begin to reciprocate and to rotate in oscillatory fashion. As the work piece rotates toward the rotating cutting element and moves to the left as viewed in Fig. 16, contact 141 also begins to scan cam segment 138 of the pair of cams 135. When physical contact between these two elements occurs, current flows to the cutting head solenoid 81 causing the cutting element to be pulled into the work piece. When the length of cut is signaled by the breaking of physical contact between the elements 141 and 138, the cutting element is withdrawn from the work and the work piece continues to rotate towards the cutting head and to reciprocate to the left and until the ends of the respective strokes are reached.

At this instant, return stroke switch 168 becomes operative to open the electrical circuit to magnet 81 and the circuit remains open during the complete return stroke of the work piece in spite of the fact that contact 141 will physically sweep over cam segment 138 in the course of the return stroke.

As soon as the first cut is complete, the appropriate feed rack and pawl, such as the rack 76 and the pawl 94, are operative in response to slide rack 27 to index the

cutting head a predetermined distance along the work piece. The appropriate driving rack has been placed in driving condition by the operation of the timing bar 97 in conjunction with rock levers 96, the timing bar, of course, having been set by the engagement of the lug 100 with the end of the slot 101 as the cutting head swung into position A in the first instance.

The cutting head is indexed along the work piece in incremental fashion until all grooves have been milled from position A. This occurrence is signaled by the engagement of depending lug 100 with the timing bar, specifically the opposite end of slot 101. Correspondingly, the trigger and latch mechanism of Fig. 3 are operative to cast the cutting head from position A to position B. During this occurrence the lug 100 drives the timing bar 97 to the left with positive motion and the timing bar, in turn, operates to (1) actuate the selector switch 143 to place the appropriate cam in circuit (2) actuates the gear change or flip-over mechanism through the instrumentality of its extension, rod 54, (3) to disengage driving index rack 76 from its pawl 94 and to render the rack and pawl operative.

Thereafter with the cutting head in position B, the work piece rotates away from the cutting head and reciprocates to the left with the result that a groove is milled in accordance with the arrow shown on the work piece in Fig. 16.

The desired number of grooves are milled from position B in the same manner as described with respect to position A. Upon the completion of all cuts from the B position, the cutting head is automatically shifted to the A' position; the selector switch shifts the current to the opposite pair of contact cam segments, the gear change device is actuated to reverse rotation of the work piece, the appropriate end rack is engaged while the other is disengaged in generally the same fashion as the occurrence of these events previously described with respect to the shifting of the cutting head from position A to position B. There is, however, one additional occurrence at this moment; namely, the clutch 118 is actuated by the lug 129 to permit the work piece to be phased through 180° so as to present work area No. 2 to the cutting head.

Thereafter the machine proceeds automatically to perform the function and operation described with respect to Fig. 16.

During the course of the operation of the checkering machine, the counter mechanism of Figs. 13 and 14 is operative in the manner previously described until ultimately, upon the completion of work area No. 2, the counter mechanism is rendered operative to shut down the machine thereafter the complete work piece W is removed and a new piece inserted. Repetition of the above described operations may then be undertaken to checker the new work piece.

It is anticipated that various modifications and arrangements may be undertaken as design considerations and engineering practices may dictate without departing from the spirit and scope of the present invention.

What is claimed is:

1. An automatic checkering machine comprising an arbor movably mounted in a frame for supporting a work piece, a cutting head mounted in the frame and movable from a normal position to a cutting position effective to cut grooves in the work piece, means for indexing the cutting head along the work while in the normal position, means for rotating and reciprocating the arbor and thus the work simultaneously with respect to the cutting head so that the cutting head while in the cutting position mills grooves of a predetermined hand and angle of lead in the stock, a first control means operable to move the cutting head from the normal position to the cutting position in accordance with a predetermined pattern and a second control means including a pair of relatively movable followers cooperating with the cutting head and the surface of the work piece effective to insure a uniform depth of cut throughout the pattern.

2. An automatic checkering machine comprising an arbor movably mounted in a frame for supporting a work piece, a cutting head mounted in the frame and movable from a normal position to a cutting position to cut a plurality of grooves in the work, means for indexing the cutting head along the stock after each groove is cut, means for rotating and reciprocating the work simultaneously with respect to the cutting head so that the cutting head while in the cutting position mills grooves of a predetermined hand and angle of lead, automatic means controlled by the indexed position of the cutting head for shifting the cutting head and shifting the motion of the work piece whereupon grooves of the opposite hand are milled, a first control means operable to move the cutting head from the normal position to the cutting position in accordance with a predetermined pattern and a second control means including a pair of relatively movable followers cooperating with the work piece and the cutting head effective to insure a substantially uniform depth of cut throughout the pattern.

3. An automatic checkering machine comprising a shaft movably mounted in a frame for supporting a work piece, a cutting head movably mounted in the frame and normally spaced from the work piece, means including an electro magnet effective to move the cutting head towards the work piece into a cutting position, means for moving the shaft and thus the work with respect to the cutting head so that the cutting head while in the cutting position mills a groove of a predetermined hand and angle of lead in the stock, electrical control means effective to regulate the electro magnet so as to control the length and continuity of said groove, and mechanical control means mounted upon the cutting head and including at least two relatively movable followers engageable with the work piece effective to insure substantially uniform depth of groove.

4. An automatic checkering machine comprising a frame, a work holder rotatably mounted in the frame and adapted to support a generally cylindrical work piece along its longitudinal axis, said work holder having a first working position and a second working position, a cutting head movably mounted on the frame, means for reciprocating and for rotating the work piece simultaneously while in said first position, means for positioning the cutting head relative to the work piece so that while the work piece is rotated and reciprocated in said first position a thread of a given hand is milled in the work piece, means for indexing the cutting head along the work automatically after said thread is milled, automatic means responsive to the indexed position of the head operable to reverse the direction of rotation of the work piece and to change the position of the cutting head whereby a thread of the opposite hand is milled, cam means including an electromagnet effective to tilt the cutting head to and fro with respect to the work piece to control the length and continuity of each thread and automatic means for shifting the work piece from said first working position to said second working position so that a new area of the work piece may be checkered.

5. An automatic checkering machine comprising a frame, a work holder rotatably mounted in the frame and adapted to support a generally cylindrical work piece along its longitudinal axis, a cutting head movably mounted on the frame, means for advancing and for rotating the work piece simultaneously, control means for positioning the cutting head relative to the work piece so that while the work piece is rotated and advanced a thread of a given hand is milled in the work piece, means for returning the work piece to its starting point, said control means being effective to tilt the cutting head away from the work piece during the return stroke, means for indexing the cutting head along the work automatically after each thread is milled, automatic means responsive to the indexed position of the head and operable after a predetermined number of threads have been milled to

reverse the direction of rotation of the work piece and to change the position of the cutting head whereby threads of the opposite hand are milled, and cam means cooperating with the control means effective to control the length and continuity of each thread of both hands whereby a pattern of checkering having a predetermined outline is formed.

6. A machine for automatically checkering a gun stock comprising a frame, a work holder supported in the frame and adapted to support a gun stock generally along its longitudinal axis, a cutting head mounted on the frame, means for moving the cutting head into engagement with the stock, means for rotating and advancing the stock simultaneously while the cutting head is in engagement with the stock effective to mill a thread in the stock, means for indexing the cutting head along the stock automatically for milling a plurality of said threads, automatic means responsive to the indexing means for reversing the direction of said rotation and for changing the position of said cutting head whereby threads of the opposite hand are milled, and cam means including an electromagnet effective to control the interval during which the cutting head is held in engagement with the stock while cutting a given thread, means for turning the stock automatically upon completion of a first checkering operation in a first area of the stock to present a new area to the cutting head and counter means responsive to the indexing mechanism operative automatically to shut down the machine after said new area has been checkered.

7. A machine for automatically checkering a wooden work piece comprising a frame, a work holder movably supported in the frame and adapted to support the work piece generally along its longitudinal axis, a cutting head mounted on the frame, means for moving the cutting head into engagement with the work, means for rotating and advancing the work simultaneously while the cutting head is in engagement with the work effective to mill a thread in the stock, means for moving the cutting head out of engagement with the work, means for returning the work piece to its starting point, ratchet means for indexing the cutting head along the stock automatically for milling a plurality of said threads, automatic means including a timing bar responsive to the indexed position of the cutting head for reversing the direction of said rotation and for changing the position of said cutting head whereby threads of the opposite hand are milled, and cam means including an electromagnet effective to control the interval during which the cutting head is held in engagement with the work while cutting a given thread, means

for turning the work upon completion of a first checkering operation in a first area so as to present a second area to the cutting head and counter means responsive to the indexing means and operative automatically to shut down the machine after a predetermined number of areas have been checkered.

8. A machine for automatically checkering a gun stock comprising a frame, an arbor carried by the frame for movably supporting the stock, a cutting head movably mounted in the frame and adapted to cut grooves in the stock, means for moving the stock with respect to the cutting head and the cutting head relative to the stock so that the head mills at least two groups of grooves therein, each group having a predetermined hand and angle of lead, control means operable to limit the length and continuity of each groove in accordance with a predetermined pattern and a second control means including at least two relatively movable followers cooperating with the cutting head and the surface of the work piece effective to insure a uniform depth of cut throughout the pattern.

9. In a wood checkering machine including a work holder and a cutting head carrying a cutting element, a device for maintaining uniformity of depth of cut in a work piece carried by the work holder where cutting occurs while the work piece and the cutting element move relative to one another comprising: a pair of followers movably mounted upon the cutting head and normally disposed in sliding contact with the surface of the work piece while the cutting element normally projects a predetermined distance beyond the followers into the work, said work piece having variations in its surface contour characterized by high and low regions, said followers being movable relative to one another along paths generally normal to the surface of the work piece so that both followers remain in contact with the work as the followers encounter said high and low regions, said predetermined distance remaining substantially constant with respect to at least one of said followers in spite of variations in surface contour of the work piece.
